UNITED STATES PATENT OFFICE.

LOUIS HONSTEIN, OF PORTLAND, OREGON.

CLAMP FOR FRUIT-JARS.

No. 901,618.

Specification of Letters Patent.

Patented Oct. 20, 1908.

Application filed May 6, 1908. Serial No. 431,269.

To all whom it may concern:

Be it known that I, LOUIS HONSTEIN, a citizen of the United States, residing at Portland, in the county of Multnomah and State 5 of Oregon, have invented a new and useful Clamp for Fruit-Jars, of which the following is a specification.

This invention relates to clamps for holding fruit jars, on a table, or other support, 10 while the cap is being screwed onto, or off of a jar.

In preserving fruit in glass jars, there is great trouble and difficulty in screwing the cap upon the jar, as the contents render the 15 jar extremely hot, making it difficult to handle the jar, while the cap is screwed on tight. Also, in unscrewing the cap, the jar must be held firmly to unscrew the cap, which is done with difficulty, as the cap becomes wedged in 20 place.

The object of this invention is to provide an improved clamp for holding a fruit jar to a table, by means of which the jar will be firmly held in place, and prevented from being 25 coming loose, and working off of the table, and by means of which also, the jar may be readily clamped in place and held from turning.

The invention consists of an improved 30 fruit jar clamp, constructed, as hereinafter set forth and claimed:

Referring to the drawing, Figure 1 is a perspective view of a fruit jar clamp constructed in accordance with this invention, 35 and shown as secured to the edge of a table. Fig. 2 is a side view thereof. Fig. 3 is a perspective view of the movable jaw detached.

The clamp consists of a circular plate 1 of iron, or wood, or other suitable material, and 40 formed at one side with a fixed curved jaw 2, adapted to fit against the side of a glass fruit jar. At the opposite side from the fixed jaw, the plate 1 is formed with an extension 3, provided with parallel slots 4, each open 45 at its outer end, and each communicating at its inner end with an opening 5 in the plate 1. An arm 6 extends between said openings 5, and projects beyond the extension 3, terminating in an upturned end, or bracket 7, the 50 arm 6 forming with the extension 3 the slots 4. Resting on the extension 3 is a curved slidable jaw 8, having on its lower edge the inclined lugs 9, which project through the slots 4, and embrace the inclined sides 10 of the arm 6, the lugs 9 serving as guides to steady the jaw 8 in its movement.

The jaws 2 and 8 each have their inner clamping surface preferably provided with a strip of rubber 11, secured thereto by glue, or otherwise, the rubber surface preventing injury to the glass jar, and holding it from slipping. The jaw 8 may be operated by any suitable means, and, as here shown, preferably by a screw shaft 12, having a crank handle 13. The screw shaft 12 extends through 60 and engages a screw-threaded hole 14 in the bracket 7, and has its forward end unthreaded and projecting into a hole in the slidable jaw 8, and connected to the jaw 8 in any suitable manner to turn freely thereon. 70

In order to firmly secure the clamp to a table, or other suitable support, the plate 1 is provided on its under side with an L-shaped bracket 15, having a clamping screw 16, extending through the bracket 15, with a 75 clamping head 17, pivoted on its outer end. To steady the plate 1 against lateral movement, when it is clamped to a table, it is provided on its under side, at a suitable distance from the bracket 15, with two lugs or projections 18, adapted to bear against the edge of a table.

When the clamp is attached to the edge of a table, the plate 1 rests on the table, as shown, and the bracket 15 and lugs 18, bear 85 against the edge 19 of the table. The clamping screw 16, bearing tightly against the under side of the table serves to hold the clamp firmly thereon, the lugs 18 at a spaced distance from the bracket 15, on either side 90 thereof holding the clamp from moving laterally when force is applied to screw on a cap, or unscrew it from a jar. A glass jar 20, as shown in dotted lines in Fig. 1, having been placed on the plate 1, with one side of its 95 lower end abutting against the fixed jaw 2, the slidable jaw 8 is advanced against the opposite side of the jar by operating the screw 12, and is brought to bear firmly against it, thereby securely holding the jaw in clamped 100 position. The clamp is adapted to hold jars of different sizes, and a jar may be easily and quickly clamped thereon by a single turn of the screw 12. A jar being firmly and rigidly clamped on a table, as herein set forth, a cap 105 can be conveniently and readily screwed on or off of the jar.

What is claimed is:—

1. A fruit jar holder comprising a base member having a fixed jaw and provided 110 with an integral clamping bracket, a clamping member carried by said bracket, that

portion of the base opposite the fixed jaw being arranged to form a guiding bar, a slidable jaw mounted on the guiding bar and means for operating the slidable jaw.

5. 2. A fruit jar holder, consisting of a base having a fixed jaw on one side, and a guide bar, and guide slots on its opposite side, a slidable jaw having guide lugs engaging said guide bar, means for operating the slidable jaw, and means for clamping the holder to a support.

10 3. A fruit jar holder, consisting of a base having a fixed jaw on one side, and a slotted projection, and guide arm with tapering 15 sides and bracket on its opposite side, a slid-

able jaw with tapering lugs engaging the slots in the projection and the guide arm, an operating screw shaft mounted in the bracket of the guide arm, and connected to the slid- 20 able jaw, a bracket with clamping screw depending from the base, and steadyng lugs on the base on opposite side from the clamping bracket.

25 In testimony that I claim the foregoing as my own, I have hereto affixed my signature in the presence of two witnesses.

LOUIS HONSTEIN.
